UNITED STATES PATENT OFFICE.

HEWITT F. BRIGGS, OF NORTH BALTIMORE, OHIO, AND WILLIAM B. BROWN, OF BALTIMORE, MARYLAND.

DESIGN FOR A CHECK-VALVE.

SPECIFICATION forming part of Design No. 31,441, dated August 22, 1899.

Application filed July 26, 1899. Serial No. 725,199. Term of patent 7 years.

To all whom it may concern:

Be it known that we, HEWITT F. BRIGGS, residing at North Baltimore, Wood county, State of Ohio, and WILLIAM B. BROWN, residing at Baltimore, State of Maryland, citizens of the United States, have invented and produced a new and original Design for Check-Valves; and we do hereby declare the following to be a full, clear, and exact description of the same, reference being had to the accompanying drawings, forming a part thereof.

The drawings represent in Figure 1 an elevation of the valve and in Fig. 2 a top plan thereof.

5 The design relates to the configuration of the valve.

The leading features of the design appear in the following description.

A is the valve proper, having the upper por-

tion concave, as at B, while projecting upwardly therefrom are the wings C. Projecting substantially centrally from the upper face of the valve is the rectangular stem D.

What is claimed as new is—

The design for a check-valve, substantially 25 as herein shown and described.

In testimony whereof we affix our signatures in presence of witnesses.

HEWITT F. BRIGGS.

WILLIAM B. BROWN.
